UNITED STATES PATENT OFFICE

1,985,246

PRINTING AND ADDRESSING MACHINE

Harmon P. Elliott, Watertown, Mass.

Application November 12, 1931, Serial No. 574,482

31 Claims. (Cl. 101—47)

This invention relates to machines for printing and addressing public service bills and is of the general type disclosed in my application Serial No. 273,364, filed April 27, 1928.

5 A public service bill, as a telephone bill, frequently consists of several connected sections, each bill having a different address and printed matter common to all of the bills; and each section of a bill having the same address. Certain 10 of the sections are adapted to be detached from the remainder of the bill for business purposes. One of the sections of the bill may be longer than the other sections of the bill. In the machine of the above identified application an electro- 15 type roll is used to apply on the bill the printed data common to all of the bills. Addressing mechanism using printing devices as stencils is employed to apply the same address on different sections of any one bill and different addresses 20 on the different bills. The bills are printed from a web of paper which is advanced through the two printing positions by being continuously engaged with an endless driving face of the electro- 25 type roll. Since the web must be stationary for the printing of the addresses, the electrotype roll is advanced intermittently in the same direction. The advancing of the electrotype roll is effected by means of a multi-toothed ratchet fixed to the 30 roll and which is engaged by a reciprocating pawl. Since one of the sections of the bill is longer than the other sections, the electrotype roll of said application is given a greater amount 35 of movement at one time than at another time. The amount of movement is obtained by having the pitch space between two consecutive teeth of the ratchet greater than between other teeth and by providing the pawl with a throw at least equal to the greatest length between teeth. With 40 this arrangement there is a considerable extent of movement of the pawl prior to its engagement with the teeth having a short distance between them and thereby strikes these teeth with a hammer blow effect which is objectionable. Consequently, one of the objects of the present 45 invention is the provision of a machine of the general type disclosed in my above identified application wherein the arrangement is such that the electrotype roll can be advanced intermittently by steps of equal length and that the teeth of the cam are equally spaced.

50 With an electrotype roll constructed as above described, it becomes necessary to have means for compensating for the uniform steps of advance of the electrotype roll for printing a multi- 55 section bill wherein one section is longer than the other sections, or wherein the sections are of unequal length. To this end, it is a further object of the present invention to employ, in combination with the above described electro- 60 type and sheet-advancing roll, means for vary-

ing the amount of advance of the paper sheet through the addressing mechanism, by causing the sheet to advance either a greater or a lesser amount than is provided by each intermittent movement of the roll, so that the addresses are 5 applied to the bill sheet the proper distance apart.

In carrying out this object of the invention, mechanism is provided which acts on the paper sheet between the printing and addressing positions to lengthen and shorten the length of the path of the paper movement between these positions in an automatic and predetermined manner. The arrangement is such that when the mechanism operates to lengthen the path, it draws a 10 certain amount of paper through the addressing position in addition to the amount drawn by the feed roll and, when the mechanism operates to shorten the path, the feed roll draws a certain 15 amount of paper from the path without advancing paper through the addressing position. For a bill having a long first section and successive shorter sections, the length of travel of the bill sheet is increased during the time that the electrotype roll is moving to print a portion of the 20 first bill section. Consequently a longer length of paper is advanced through the addressing position than is directly advanced by the electrotype roll, so that the bill sheet is brought into proper 25 position for the printing of the address on the first bill section. At the time the electrotype roll is next advanced, for the printing of the next and shorter bill section, the length of the path of the bill sheet is shortened so that the length of 30 paper that is drawn through the address position is less than the amount of movement of the electrotype roll and consequently the bill sheet is in proper position to receive the second address. Such an arrangement constitutes a further 35 object of the invention.

The sections of the bill are made detachable from each other by a line of scoring which extends transversely of the bill between the sections. Some bills have but a single score line 45 between two of the consecutive sections while others may have score lines between each two consecutive sections. In scoring or perforating the first type of bill, the scoring mechanism can be located between the electrotype roll and the paper feed compensating mechanism, while for the second type of bill the scoring mechanism is located between the paper feed compensating mechanism and the addressing mechanism. A machine adapted to receive the perforating mechanism in either one of these two positions comprises a further object of the present invention.

Accuracy of registration between the addresses and the printed matter of the bills is essential. Over-travel of the electrotype roll may impair 50 accuracy of registration. Consequently a further 55 60

object of the invention is the provision of mechanism which positively holds the electrotype roll against over-travel from the positions in which it is successively moved.

5 A further object of the invention is generally to improve the construction and operation of bill printing and addressing machines.

Fig. 1 is a side elevation of the bill printing and addressing machine embodying the present 10 invention.

Fig. 2 is a plan view of the machine of Fig. 1.

Fig. 3 is a longitudinal elevation through the machine of Fig. 2 and illustrating diagrammatically the relation between the various parts of the 15 apparatus.

Fig. 4 is a plan detail similar to Fig. 2 but illustrating the perforating mechanism located between the paper feed compensating mechanism and the addressing position.

20 Fig. 5 is a diagrammatic view similar to Fig. 3 and illustrating the relative relation of the essential parts of the apparatus of the modification of Fig. 4.

Fig. 6 is a section taken along line 6—6 of Fig. 1, 25 and illustrating particularly the electrotype and platen rolls.

Fig. 7 is a longitudinal sectional view of the electrotype roll taken along line 7—7 of Fig. 6.

Fig. 8 is an end view of the electrotype roll taken 30 along line 8—8 of Fig. 7.

Fig. 9 is a view taken along line 9—9 of Fig. 7.

Fig. 10 is a view of a completed printed and addressed bill comprising one of the products of the present machine.

35 Fig. 11 is a view of a bill similar to the one illustrated in Fig. 10 except that it has lines of perforations between each two consecutive sections.

Fig. 12 is a plan view of an address bearing bill sheet prior to printing the body of the bill 40 thereon.

Fig. 13 is an end elevation of the sheet-feed compensating mechanism, taken along line 13—13 of Fig. 2.

The machine here shown includes a table 16 having extended longitudinally thereof a stencil track 18 along which stencils 20 are advanced in successive order from a stencil holder 22 and delivered to an elevating mechanism 24 which delivers the stencils into a stencil receiver 26.

50 The successive lowermost stencils in the stencil holder 22 are moved from the pile into and along the track by a stencil pusher 28 which has a releasable connection with a pusher-reciprocating connecting rod 30 that is reciprocated by an arm 55 32. Said arm in turn is reciprocated by a cam member 34 connected to a shaft 36 that is reciprocated by a connecting rod 38 from a suitable power mechanism 40. Mechanism illustrated in my above identified application and not herein shown, 60 is provided to break and establish connection between the pusher 28 and the connecting rod 30 so that a stencil is moved from the stencil holder into the track only after a predetermined number of reciprocatory movements of the connecting rod. For the printing of the bill illustrated in Fig. 10 where the same address is printed four times in different portions of the bill, the pusher is operated to move a stencil from the holder into and along the track only after each fourth operation 70 of the connecting rod.

75 Printing mechanism comprising a platen 42 and a printing roller 44 are disposed on opposite sides of the stencil track and are adapted to reciprocate toward and away from each other to print the address carried by a stencil disposed

therebetween upon a web or sheet 46 of paper located under the stencil track.

The bill sheet 46 is contained in a roll 48 freely supported in bearings 50 of the frame of the machine. The sheet is withdrawn from the roll by co-acting upper and lower rolls 51 and 52, between the bite of which the paper sheet passes. The roll 52 is constantly driven at a peripheral speed which is slightly in excess of the average rate of advance of the sheet through the addressing and printing portions of the mechanism so that the paper forms into a loop 54 which gradually lengthens. The feed of the paper at this point can be arrested momentarily by raising the paper roll 51 from pressure engagement with the sheet on the roll 52 by depressing the lever 56 and holding it depressed until a sufficient amount of paper has been withdrawn from the loop. The paper sheet passes out of the loop over a guide roll 58 and thence to the right under the stencil track and through the printing position where it passes around a bar 60 and thence passes to the left still under the stencil track and between the platen 42 and the printing roll 44 of the addressing mechanism and to the engagement of the upper electrotype roll 62 and lower platen roll 64, where the printed data on the body of the bill is applied.

The bill 66 illustrated in Fig. 10 comprises a long section 68 and consecutive shorter sections 30 70, 72 and 74, which shorter sections may or may not be equal in length. The particular bill of Fig. 10 is provided with a line of scoring or perforations 76 which extend transversely of the bill between the long section 68 and the first short section 70, there being no perforations between the sections 70 and 72; and 72 and 74. In Fig. 11 there is a line of scoring or perforations between each two contiguous sections. The body of the bill has printed matter 78 thereon which is common to all of the bills, although the printed matter may be different at least in part in the various sections of each bill. Each bill also bears the address matter 80 which is duplicated in the various sections of the bill. Successive bills, 45 however, have different addresses. The address matter may also include other matter 82 such as the base rate for service. The address matter must be in accurate registration with the printed matter 78 not only in any one bill but in successive bills. The address matter is contained in the stencils and is applied while the sheet is held stationary in addressing position between the platen 42 and the printing roller 44 and is applied as shown in Fig. 12 prior to the printing of the common data 78 on the bill. Since the section 68 of the bill is longer than the other sections thereof, it is apparent that the bill sheet must be moved a greater distance from the end of the section 74 of one bill to the addressing position on the section 80 of the next succeeding bill, than it is to be moved for applying the addresses to the shorter sections of the bills.

In my above named application, the electrotype roll, which carries the electrotype for printing the common data 78, and the cooperating platen roll are advanced intermittently by steps of variable length sufficient to advance the paper the various distances that are necessary to position the paper sheet in proper position to receive the addresses thereon. In accordance with the present invention, however, the electrotype and platen rolls are advanced intermittently by steps of equal length and other means are provided to compensate for the, at times insufficient 70 75 80 85 90 95 98 99 100

and at other times over-sufficient, extent of advance of the sheet by the electrotype rolls. The electrotype roll, see Figs. 1, 6, 7, is provided with means for holding on its periphery electrotype plates 84 which print the common data 78 on the body of the bill. The electrotype roll comprises a sectional drum 86 secured to a hub 88 that is fixed by a key 90 to a sleeve 92. Said sleeve is rotatably supported on a shaft 93 journaled in upstanding bearing brackets 94 of the frame of the machine. A flange 96 is secured to said hub at one side of the drum 86 and carries a gear 98 that meshes with a similar gear 100 fixed to the shaft 102 of the cooperating platen roll so that the two rolls rotate together. The drum 86 of the electrotype roll is provided with a continuous peripheral flange 104 which, preferably is knurled, and is in constant engagement with the paper sheet between it and the platen roll so that the paper sheet is caused to advance whenever the electrotype and platen rolls are advanced. The electrotype roll is advanced by intermittent steps of equal length by the oscillatory movement of the shaft 93. A ratchet 106 is fixed by the key 90 to one end of the sleeve 92 partly within the gear 98. The ratchet, see especially Fig. 8, is provided with four teeth 108 which are equidistantly spaced around the periphery of the ratchet. The shaft 93 has an arm 110 fixed thereto and pivotally carries at its free end a pawl 112 having a detent 114 that is adapted to engage any one of the teeth 108 of the ratchet. A spring 116 is extended between the free end of the pawl and an extension 118 of the arm 110 to maintain the detent in constant engagement with the ratchet. The amount of oscillatory movement of the shaft 93 is such as to move the detent 114 just behind all of the successive teeth 108 of the ratchet so that, upon rotary movement of the shaft 93 in the opposite direction, the ratchet and consequently the electrotype roll is caused to be advanced one-fourth of a revolution. Oscillatory movement is imparted to the shaft 93 by means of a pinion gear 119 which is fixed to the shaft and is in mesh with the teeth of a rack 120, which rack is vertically reciprocable in grooves in the table 16 and also in an extension 122 of one of the bearing brackets 94. The rack is reciprocated by means of a connecting rod 124 which is adjustably screw-threaded at its upper end in a yoke 126 that is pivotally connected by a screw 128 to the rack. The lower end of the connecting rod is screw-threaded adjustably in an eccentric strap 130 that encircles an eccentric 132 fixed to the drive shaft 134. The screw-threaded connections between the eccentric strap 130 and yoke 126 are respectively right and left hand so that the effective length of the connecting rod can be varied thereby to vary the positions in which the electrotype roll is held at rest.

The shaft 134 is supported in suitable bearings beneath the table 16 and is driven through a chain 136 by the power mechanism 40 in timed relation with the operation of the stencil printing and moving mechanism. The shaft 134 also drives through a pinion gear 138 and an idler gear 140, a large gear 142 fixed to a counter-shaft 144 that is journaled above the table 16. Said shaft operates the stencil elevating mechanism 24 and various other essential components of the machine as will presently appear. The electrotype roll is inked by inking rolls 146, see Figs. 1 and 6, which, as in my prior application, are moved into engagement with the electrotype roll just prior to the start of its movement and out of engage-

ment with said roll at the time it stops rotating. The mechanism for controlling such movement of the inking rolls includes a four-lobed cam 148 fixed to and rotatable with the shaft 144. Since, in the present invention the electrotype roll advances by steps of equal length, the distances between the successive lobes of the cam 148 are equal.

Since the electrotype roll advances the bill sheet by steps of equal extent, mechanism is provided to compensate for such equal steps by causing the paper sheet to advance sometimes more and sometimes less than the extent of movement provided by the electrotype roll, whereby to convert such movement of the sheet into steps of different length. Such mechanism is illustrated especially in Figs. 1, 3 and 13.

The paper feed compensating mechanism, indicated generally by the numeral 150, is located between the electrotype rolls and the address printing mechanism and includes a roller 152 that is located beneath the paper sheet. Said roll is journaled in upstanding guide members 154 that are slidable in guide brackets 156 secured to the base 16 on opposite sides of the paper sheet. Said guide members are provided with outstanding pins 158 at their upper ends on which rollers 160 are journaled. Said rollers are received in elongated slots 162 of arms 164 that are fixed to a shaft 166 journaled in extensions of said guide brackets. The shaft 166 with its arms 164, when raised and lowered, provides means to raise and lower the paper engaging roll 152. Idler rolls 168 and 170 are extended between and are journaled in the guide brackets 156 above the paper sheet and on opposite sides of the sheet-raising roll 152. It is apparent that if said roller 152 is raised from a lowered position into, say, the position illustrated in Fig. 13 at the same time that the electrotype roll is advanced one step, or subsequent the advance of the roll and prior to the operation of the stencil printing mechanism, the paper sheet will be deflected laterally and hence moved through the addressing position by an amount which is in excess of the amount caused by the movement of the electrotype roll. Furthermore if the paper-feed compensating or deflecting roll 152 is lowered during the movement of the electrotype roll, a lesser length of paper will be drawn through the addressing position than is advanced by the electrotype roll, the difference being made up by causing the electrotype roll to draw paper from the length of paper between it and the idler roll 168 and over the depressed roll 152. Thus in the addressing of the first or long section 68 of the bill sheet, the electrotype roll advances to advance the paper sheet a part of the required distance and the paper-feed compensating roll 152 is elevated sufficiently to advance the paper sheet the remaining distance required to position the address at the proper place on the bill sheet to register with the common matter printed by the electrotype roll. Since the second section 70 of the bill is shorter than the peripheral length of movement of the electrotype roll, in its second advance the roll ordinarily would advance the paper sheet too much through the addressing position. Consequently the paper-feed compensating roll 152 is lowered a sufficient amount to equalize or compensate for the paper feed so that the paper sheet is advanced through the addressing position a lesser distance than it is advanced under the electrotype roll. At some time between the beginning of the advance of the electrotype roll for

the printing of the third bill section and the operation of the addressing mechanism the roll 152 is moved a further distance downward by an amount sufficient to cause the succeeding address 5 to be printed in the proper place on the sheet. The positions of the paper-sheet compensating roll 152 are controlled by a cam 172 fixed to a shaft 174 driven by gears 176 from the drive shaft 144 and operating in suitably timed relation with 10 the electrotype roll and the associated component parts of the machine. The cam rotates in engagement with a roll 178 journaled on a screw 180 fixed to an arm 182 which is loose on the shaft 166 and bears against and is secured to an arm 164 thereof. The securing means comprises a screw 184 that is screw-threaded in the arm 164 and is disposed in a transversely-elongated slot 186 so that the supporting frame for the roll 152 can be raised and lowered with respect to the cam and 15 cam roller. This construction provides means for obtaining an initial adjustment of the length of the paper path between the printing positions of the electrotype roll and the addressing mechanism and thus obviates the necessity for accurately setting said mechanisms the requisite distance apart.

The cam 172 is provided with as many lobes as there are sections of the bill to be printed. In the present instances, since the bill has four sections, 20 the cam has four lobes 188, 190, 192 and 194, the lobes being of such successively different heights as are sufficient to position the paper sheet in the proper location to receive the successive addresses. When the electrotype roll rotates for the 25 printing of a part of the first section of the bill the cam rotates to pass the roller 178 from the lobe 194 to the lobe 188. This action raises the paper-feed compensating roller 152 and thereby draws a length of paper through the addressing position 30 in addition to the amount drawn by the electrotype roll. On the next movement of the electrotype roll the lobe 188 passes out from under the roller 178 and permits this roller to drop upon the next lower lobe 190 so that a shorter length of 35 paper is moved through the addressing position than is advanced by the electrotype roll, the difference being drawn from the path of sheet-travel between the electrotype roll and the addressing position, the length of which path is shortened by 40 the descent of the compensating roll 152. During the next advance of the electrotype roll the next succeeding lobe 192 of the cam comes into action and so on until a complete bill has been addressed 45 and printed. The cam 172 need not rotate precisely in phase with the electrotype roll but the action of the cam should take place prior to the operation of the stencil printing mechanism so that the paper is stationary at the time the 50 addresses are printed. It will be noted that the 55 paper sheet is constantly engaged by the driving face of the electrotype roll and that this roll effects the advance of the paper although, by changing the length of the path of the sheet between the electrotype roll and the addressing position, the 60 action of the electrotype roll in advancing the sheet is modified to compensate for the different lengths of advance of the sheet that are necessary for the address of the respective sections of the 65 bill.

In order to prevent over-travel of the electrotype roll and thereby of the paper sheet, mechanism is provided which releasably engages the roll and positively locks it against undesired advance 70 due to its inertia. This mechanism is illustrated

in Figs. 6, 7 and 9. The sleeve 92 of the electrotype roll has fixed thereto a ratchet 196 which has four equally spaced teeth 198 thereon. A locking arm 200 is pivoted at 202 to a bracket 204 which is secured to one of the bearing brackets 94 and is 10 secured in vertically-adjusted position by screws 206 which are threaded into the bracket 204 and passed through vertically-elongated slots 208 in the bracket 204. The locking arm 200 has a 15 detent 210 which is adapted to engage any one of the teeth 198 thereby to hold the electrotype roll from rotation. The locking arm is urged constantly into locking position with the ratchet by a spring 212. The locking arm is moved away from holding engagement with the ratchet by a 20 cam 214 which is fixed to the oscillating shaft 93 of the electrotype roll and engages a roller 216 of the locking arm. When the shaft 93 is reciprocated in a clockwise direction, Fig. 8, so as to cause the detent 210 to engage the next following tooth 108 of the ratchet 106, the cam 214 is positioned under roller 216 and thereby holds the locking arm 200 away from engagement with its ratchet. During the first part of the following movement of the shaft 93 in the following direction, thereby to advance the electrotype roll, the cam 214 maintains the locking arm away from engagement with the ratchet so that the tooth of the ratchet can pass under the detent 210. Prior to the full advance of the electrotype roll and 30 ratchet, however, the cam passes from under the cam roller 216 and permits the locking arm to move into position in front of the tooth and thereby prevents the electrotype roll from advancing a materially greater distance than it is 35 definitely advanced by the shaft 93.

After the bill strip passes through the electrotype and platen rollers, it is severed between successive bill forms by a knife 218, see Figs. 1 and 2. The knife is operated from a cam 220 carried by 40 the shaft 144 in the manner described in my original application.

The bill form has a line of perforations extended transversely across it between certain of the sections. In Fig. 10, the bill has a single line of perforations 76 between the long section 68 and the first short section 70. The perforating or scoring mechanism includes an arm 222 pivoted on a bracket 224 and operated and reciprocated by a cam 226. Said arm operated cam carries a toothed blade 228 that is located above the paper and is depressible into a slot in an anvil 230 disposed therebeneath. For perforating the bill of Fig. 10, the perforating device is located between the electrotype roll and the paper-feed compensating mechanism as illustrated in Figs. 1 and 2. When, however, the bill sheet is provided with lines of perforations located between each two consecutive sections of the bill as illustrated in Fig. 11, the perforating mechanism is disposed between the paper-feed compensating mechanism and the stencil printing mechanism as illustrated in Figs. 4 and 5 where the extent of paper movement under the perforating plate is the same as between the address printing mechanism for each 60 section.

I claim:

1. A bill printing and addressing machine having addressing mechanism for printing repetitions of the same address on different sections of the same bill and different addresses on different bills, some of the sections being of different lengths, printing mechanism for printing the same data on different bills, and mechanism for advancing a sheet of paper through said printing 75

- and addressing mechanisms including sheet advancing means which advances the bill sheet intermittently by steps of constant length, and sheet-feed compensating means which changes 5 the length of said steps of sheet-advance through said addressing mechanism.
2. A bill printing and addressing machine having addressing mechanism for printing repetitions of the same address on different sections 10 of the same bill and different addresses on different bills, some of the sections being of different lengths, printing mechanism for printing the same data on different bills including printing means which is successively intermittently operated to print successive equal lengths of data on the bills, and sheet-advancing means including means which advances the bill sheet intermittently by steps of equal length at said printing mechanism and other means which advances 15 the bill sheet intermittently by steps of different lengths at said addressing mechanism.
3. A bill printing and addressing machine having addressing mechanism for printing repetitions of the same address on different sections of 20 the same bill and different addresses on different bills, some of the sections being of different lengths, printing mechanism for printing the same data on different bills including a rotary printing roll, means for advancing said roll intermittently by successive steps of equal length, and sheet advancing mechanism including means which advances the bill sheet intermittently by steps of equal length through said printing roll and other means which advances the bill sheet 25 intermittently by steps of different length through said addressing mechanism.
4. A bill printing and addressing machine having addressing mechanism for printing repetitions of the same address on different sections of 30 the same bill and different addresses on different bills, some of the sections being of different lengths, printing mechanism for printing the same data on different bills including a rotary printing roll, means for advancing said roll intermittently by successive steps of equal length, and sheet advancing mechanism including means which advances the bill sheet intermittently by steps of equal length at said printing roll, and other means which converts the intermittent advance of the sheet by steps of equal length to an 35 intermittent advance by steps of different length at said addressing mechanism.
5. A bill printing and addressing machine having addressing mechanism for printing repetitions of the same address on different sections of 40 the same bill and different addresses on different bills, some of the sections being of different lengths, printing mechanism for printing the same data on different bills, and mechanism including means for advancing a bill sheet intermittently at said printing mechanism by steps of equal length and other means for advancing the bill sheet intermittently at said addressing mechanism by steps of different lengths.
6. A bill printing and addressing machine having addressing mechanism for printing repetitions of the same address on different sections of 45 the same bill and different addresses on different bills, some of the sections being of different lengths, printing mechanism for printing the same data on different bills, and mechanism for advancing a bill sheet intermittently at said printing mechanism by steps of equal length and other means for advancing the bill sheet intermittently at said addressing mechanism by steps of different lengths, said sheet advancing mechanism in- 50
- cluding means which advances the bill sheet through both said printing and addressing mechanisms and has means for advancing the sheet intermittently by steps of equal length, and means which modifies the lengths of said steps at said addressing mechanism.
7. A bill printing and addressing machine having addressing mechanism for printing repetitions of the same address on different sections of the same bill and different addresses on different bills, some of the sections being of different lengths, printing mechanism for printing the same data on different bills, and mechanism for advancing a bill sheet intermittently at said printing mechanism by steps of equal length and 55 at said addressing mechanism by steps of different lengths, said sheet advancing mechanism including means which acts to advance the bill sheet through both said printing and addressing mechanisms intermittently by steps of equal length, and means for converting such movement of the sheet into an intermittent advance by steps of different length at said addressing mechanism.
8. A bill printing and addressing machine comprising mechanism for printing the same data on successive bill sheets, addressing mechanism for applying addresses on successive bill sheets, and means for advancing the bill sheet intermittently by steps of equal length through 60 said printing mechanism and by steps of unequal length through said addressing mechanism so that said addressing mechanism is caused to apply addresses at different distances apart on the bill sheet in register with the printed data thereon.
9. A bill printing and addressing machine comprising intermittently-operated printing mechanism for printing the same data on successive bill sheets, addressing mechanism for applying different addresses to successive bill sheets and repetitions of the same address to any one bill sheet, and means to advance a bill sheet through both mechanisms and through the printing mechanism intermittently by steps of equal lengths and through said addressing mechanism intermittently by steps of unequal length.
10. A bill printing and addressing machine having intermittently-operated addressing mechanism for printing repetitions of the same address on different portions of the same bill and different addresses on different bills, some of the sections being of different length, intermittently-operated printing mechanism for printing the same data on successive bills, means for advancing the sheet through both mechanisms including means for advancing the sheet intermittently by steps of equal length through said printing mechanism, and means which provides different lengths of travel of the sheet between said mechanisms for causing the sheet to advance intermittently by steps of different lengths through said addressing mechanism.
11. A bill printing and addressing machine having intermittently-operated addressing mechanism for printing repetitions of the same address on different portions of the same bill and different addresses on different bills, some of the sections being of different lengths, intermittently-operated printing mechanism for printing the same data on successive bills, means for advancing the sheet through both mechanisms including means for advancing the sheet intermittently by steps of equal length through said printing mechanism, and means which at times lengthens 70
- 75

- and at other times shortens the path of travel of the sheet between said mechanisms for causing the sheet to advance intermittently by steps of different lengths through said addressing machine.
12. A bill printing and addressing machine having intermittently-operated addressing mechanism for printing repetitions of the same address on different portions of the same bill and different addresses on different bills, some of the sections being of different length, intermittently-operated printing mechanism for printing the same data on successive bills, means for advancing the sheet through both mechanisms including means for advancing the sheet intermittently by steps of equal length through said printing mechanism, and means which reciprocates transversely of and in engagement with the sheet and which raises and lowers a portion of the sheet between said mechanisms for causing the sheet to advance intermittently by steps of different length through said addressing machine.
13. A bill printing and addressing machine for printing common data on successive bills and differently spaced addresses on the bills, comprising printing mechanism, addressing mechanism, said printing mechanism including means for advancing a sheet therethrough including sheet-feed rolls, means for operating said rolls to advance the sheet through said printing mechanism by steps of equal length, and means for causing the sheet to advance through said addressing mechanism intermittently by steps of different lengths including a member disposed between said mechanisms upon which the sheet is moved, and means for holding said member in positions of different elevations whereby to change the length of the path of travel of the sheet between said mechanisms.
14. A bill printing and addressing machine for printing common data on successive bills and differently-spaced addresses on the bills, comprising printing mechanism, addressing mechanism, said printing mechanism having means for advancing a sheet therethrough including sheet-feed rolls, means for operating said rolls to advance the sheet by steps of equal length, and means for causing the sheet to advance through said addressing mechanism intermittently by steps of different lengths including a member disposed between said printing and addressing mechanisms upon which the sheet is moved, and arranged to assume any one of several differently elevated positions, and means operating at predetermined positions of said printing mechanism for determining the elevation of said member, whereby to change the length of the path of travel of the sheet between said mechanisms.
15. Printing mechanism comprising the combination of intermittently-operated addressing mechanism, means for advancing a sheet through said mechanism, means for operating said advancing means to advance the sheet intermittently by steps of equal lengths, and means to convert such advance of the sheet into an intermittent advance by steps of unequal lengths at said addressing mechanism.
16. Printing mechanism comprising the combination of intermittently-operated addressing mechanism, means for advancing a sheet through said mechanism, means for operating said advancing means to advance the sheet intermittently by steps of equal lengths, and sheet-movement converting means which changes the length of the steps in said addressing mechanism.
17. Printing mechanism comprising the combination of intermittently-operated addressing mechanism, means for advancing a sheet through said mechanism, means for operating said advancing means to advance the sheet intermittently by steps of equal lengths, and means to cause the sheet to advance through said mechanism by steps of unequal length, including means providing different lengths of travel of the sheet between said advancing means and said addressing mechanism.
18. Printing mechanism including the combination of addressing mechanism, means for advancing a sheet through said mechanism, means for operating said advancing means to advance the sheet thereat intermittently by steps of equal length, and means for causing the sheet to advance by steps of different lengths through said mechanism including a member disposed between said advancing means and said mechanism and upon which the sheet moves and adapted to be located in any one of several elevations to support the sheet thereat, and means operating in timed relation with the operation of said advancing means for raising and lowering said member.
19. Printing mechanism including the combination of reciprocating addressing mechanism, a feed roll for advancing a sheet through said mechanism, means for advancing said roll intermittently by steps of equal length, and mechanism for causing the sheet to advance through said addressing mechanism by steps of unequal length including a roller located between said feed roll and said mechanism and adapted to be raised and lowered under the sheet to raise and lower the sheet, and means operating in timed relation with the advance of said feed roll for determining the elevated position of said roller.
20. Printing mechanism including the combination of reciprocating addressing mechanism, a feed roll for advancing a sheet through said mechanism, means for advancing said roll, and mechanism for causing said sheet to advance through said addressing mechanism intermittently by steps of different length including a roller located between said feed roll and said mechanism and adapted to be raised and lowered under the sheet to raise and lower the sheet, and means operating in timed relation with the rotation of said feed roll for raising said roller into a plurality of different elevations and for lowering the roller therefrom.
21. Printing mechanism including the combination of reciprocating addressing mechanism, a feed roll for advancing a sheet through said mechanism, means for advancing said roll, and mechanism for causing said sheet to advance through said addressing mechanism intermittently by steps of different length including a roller located between said feed roll and said mechanism and adapted to be raised and lowered under the sheet to raise and lower the sheet, idler rolls disposed above the sheet on opposite sides of said roller, and means operating in timed relation with the rotation of said feed roll for raising said roller intermittently into a plurality of different elevations and for lowering the roller therefrom and for thereby raising and lowering the sheet between said idler rolls.
22. Printing mechanism including the combination of reciprocating addressing mechanism, a feed roll for advancing a sheet through said mechanism, means for advancing said roll, a roller located between said feed roll and said mechanism and adapted to be raised and lowered

under the sheet to raise and lower the sheet, a reciprocable frame supporting said roller, a stepped cam for holding said frame at times stationary in positions of different elevation, and 5 means for rotating said cam and said feed roll in timed relation.

23. Printing mechanism including the combination of reciprocating addressing mechanism, a feed roll for advancing a sheet through said mechanism, means for advancing said roll intermittently by steps of equal length, a roller located between said feed roll and said mechanism, and adapted to be raised and lowered under the sheet to raise and lower the sheet, a reciprocable frame 10 supporting said roller, a pivoted arm having a variable connection with said frame by which the elevation of said roller can be adjusted without changing the angular setting of said arm, a cam acting on said arm to raise and lower it, and 15 means for rotating said cam and said feed roll in timed relation.

24. Printing mechanism comprising the combination of addressing mechanism, feed rolls which advance a paper sheet through said mechanism, 25 and a member which is located under and is engaged by the sheet between said feed rolls and said mechanism which rises intermittently into positions of different elevation and falls therefrom to raise and lower the sheet by different 30 amounts and to control the movement of the sheet through said mechanism.

25. Printing mechanism comprising the combination of addressing mechanism, feed rolls which advance a paper sheet intermittently by equal 35 steps through said mechanism, and which converts the advance of the sheet by said feed rolls into steps of unequal length including a member which is located under and is engaged by the sheet between said feed rolls and said mechanism, and means including a stepped cam which 40 operates in timed relation to the operation of said mechanism and which raises and lowers said member and consequently the sheet to control the movement of the sheet through said 45 mechanism.

26. Printing mechanism comprising the combination of addressing mechanism, feed rolls which advance a paper sheet through said mechanism, a member which is located under and is 50 engaged by the sheet between said feed rolls and said mechanism, and means including a stepped cam which operates in timed relation to the operation of said mechanism and which raises and lowers said member and consequently the 55 sheet by amounts that are successively different to control the movement of the sheet through said mechanism.

27. Printing mechanism comprising the combination of addressing mechanism, feed rolls which 60 advance a paper sheet intermittently by steps of equal length through said mechanism, and means to convert said equal steps into unequal steps including a member which is located under and is 65 engaged by the sheet between said feed rolls and said mechanism, and means to raise and lower the sheet including a cam having steps of unequal height which operates in timed relation to the operation of said mechanism and which moves said member into positions of different elevation 70 to control the movement of the sheet through said mechanism.

28. A bill printing and addressing machine having addressing mechanism for printing repetitions of the same address in different sections of the same bill and different addresses on different bills, some of the sections being of different lengths, printing mechanism for printing the same data on different bills, and mechanism for advancing a paper sheet through said printing and addressing mechanism including sheet-advancing rolls comprising a part of said printing mechanism, 10 and a member which is located under and is engaged by the sheet between said rolls and said addressing mechanism and which rises and falls in timed relation to the operation of said addressing mechanism and which raises the sheet by 15 amounts that determine the position of the addresses on the sheet.

29. A bill printing and addressing machine having addressing mechanism for printing repetitions of the same address in different sections 20 of the same bill and different addresses on different bills, some of the sections being of different lengths, printing mechanism for printing the same data on different bills, and mechanism for advancing a paper sheet through said printing 25 and addressing mechanism including sheet-advancing rolls comprising a part of said printing mechanism, and a member which is located under and is engaged by the sheet between said rolls and said addressing mechanism and which rises and falls in timed relation to the operation of said addressing mechanism and which controls the 30 length of the paper sheet between said feed rolls and said addressing mechanism and thereby the 35 position of the successive addresses on the sheet.

30. A bill printing and addressing machine having addressing mechanism for printing repetitions of the same address in different sections of the same bill and different addresses on different bills, some of the sections being of different lengths, 40 printing mechanism for printing the same data on different bills, mechanism for advancing a paper sheet through said printing and addressing mechanism including sheet-advancing rolls comprising a part of said printing mechanism, and a member which is located under and is engaged by the sheet between said rolls and said addressing mechanism and which moves in timed relation to the operation of said addressing mechanism into differently-elevated positions that 45 determine the position of the successive addresses 50 on the sheet.

31. A bill printing and addressing machine having addressing mechanism for printing repetitions of the same address in different sections of the same bill and different addresses on different bills, some of the sections being of different lengths, printing mechanism for printing the same data on different bills, and mechanism for advancing a paper sheet through said printing and addressing mechanism including sheet-advancing rolls comprising a part of said printing mechanism, and a member which is engaged by the sheet between said rolls and said addressing mechanism and which rises and falls to change the length of the path of travel of the sheet between said rolls and said addressing mechanism by amounts that determine the position of the successive addresses on the sheet.

HARMON P. ELLIOTT.
